ABSTRACT: A rotary tubular furnace having a cooling zone comprising an array of passages for conveying the furnace charge to a discharge station. The passages are disposed around the furnace and extend generally parallel to its axis from the furnace discharge end. Conical sections oriented with axes generally parallel and offset from each other are coupled in tandem to form passages which retard the issuance of the charge and enhance its cooling.

ROTARY FURNACE

FIELD OF THE INVENTION

This invention relates to rotary tubular furnaces and more particularly to such furnaces having cooling passages from the outlet for cooling the furnace charge.

BACKGROUND OF THE INVENTION

Heretofore, rotary tubular furnaces have been provided with a plurality of cooling passages disposed in satellite relationship on the periphery of the furnace tube shell. These passages have been of a conical form expanded in the direction of material flow and have been connected to the outlet of the rotary tubular furnace by feedpipes. In order to control the movement of the material to be cooled, it has been known to provide the single-piece conical cooling passages with internal baffles. Such coolers pass the material through the cooling passages too quickly so that the material is not cooled sufficiently.

SUMMARY OF THE INVENTION

According to the invention rotary tubular furnaces are provided with a plurality of cooling pipes wherein each cooling pipe comprises at least two conical pipe portions disposed in axial sequence and offset in parallel from each other by at least the difference between the major and minor cone radii.

The object of the invention is to form the cooler for a rotary tubular furnace of the type mentioned in such manner that the period spent by the material in the cooling pipes is sufficient for intensive cooling.

This type of cooling pipe construction in accordance with the invention means that a single straight line inclined towards the cooling pipe outlet or a step dropping towards the outlet is only formed at the transition or connecting points between the individual conical pipe portions during part of each rotation of the rotary tubular furnace. During the remaining part of each rotation however, steps rising towards the outlets are present between the succeeding individual conical pipe portions. In this manner the movement of the material through the cooling pipe is retarded during a considerable part of the rotation of the tubular furnace, and only favored once during each rotation. In this manner the desired prolongation of the period spent by the material in the cooling pipes is achieved. The desired duration can be influenced by the choice of a suitable axially parallel offsetting of the conical pipe portions. In this manner it is possible to adapt to the particular objective for which the furnace is used.

In order to achieve reliable feeding of material to the cooling pipe outlet, the conical inclination of the conical pipe portions should be at least twice as great as the inclination of the rotary furnace, and preferably twice to four times as great.

It is also desirable for the axes of the conical pipe portions of all the cooling pipes to lie on an imaginary cylindrical surface concentric with the rotary furnace. A construction of this type in accordance with the invention gives a compact design, economical of space, for the rotary furnace and cooler.

DESCRIPTION OF THE DRAWINGS

These and further details of the invention will appear from the following description of certain embodiments shown in the drawings. In these:

FIG. 1 is a schematic longitudinal view of a first embodiment according to the invention;

FIG. 2 is a cross section of the line II-II of FIG. 1;

FIG. 3 is a schematic longitudinal view of a slightly altered second embodiment; and

FIGS. 4-7 are schematic longitudinal view and cross sections of two further embodiments of the invention.

DESCRIPTION OF THE PREFERRED EMBODIMENTS

FIGS. 1 and 2 show a rotary tubular furnace 1 whose cooler comprises a number of cooling pipes 2, 3, 4 and 5 disposed in

satellite manner on the periphery of and extending back along the length of the rotary furnace, these pipes being conically expanded in the direction of material flow (arrow 6). The inlets of the cooling pipes are connected to the outlet 11 of the rotary furnace 1 by means of feedpipes 7, 8, 9, 10.

Each of the cooling pipes 2, 3, 4 and 5 shown in the drawing consists of three conical pipe portions 2a-2c, 3a-3c, 4a-4c and 5a-5c disposed in axial sequence, said portions being in this embodiment axially parallel offset from each other by the difference between the major and minor cone radii, wherein the conical inclination S of all the pipe portions (e.g. 3a) is at least twice the inclination S' of the rotary furnace 1 relative to the horizontal H. The end faces of the conical pipe portions lie in planes which run perpendicular to the longitudinal axes of the corresponding pipe portions. In order to produce a compact construction of the rotary furnace 1, the axes of the conical pipe portions 2a-5c of all the cooling pipes 2-5 lie on an imaginary cylindrical surface 12 concentric with the rotary furnace 1. This furnace 1 is surrounded by an annular outlet housing 13 wherein terminate the outlet ends of all the cooling pipes 2-5. The outlet sides of the cooling pipes are thus directed towards the inlet end of the rotary furnace 1, which also contributes to the spatial economy of the furnace construction. While the cooling pipe 2-5 are fixedly attached to the rotary furnace 1, the common outlet housing 13 can be made stationary.

In the operating condition of rotary furnace 1, the heated material from the furnace outlet moves for the purpose of cooling through the feedpipes 7-10 into the inlets of the cooling pipes 2-5 which constitute the cooler. Due to the rotary movement of the furnace 1 and the sufficiently large conical inclination S of the individual pipe portions 2a-5c, the material is fed in each conical pipe portion to the end face with the large diameter. The passage of material from one conical pipe portion e.g. with the index letter a to the next (e.g. with the reference letter b) is either favored or else hindered to a greater or lesser degree, depending on the rotational position of the furnace 1.

If the embodiment in FIGS. 1 and 2 is considered, it readily will be noted that with the construction of cooling pipes 2-5 in accordance with the invention, the connecting points between the individual conical pipe portions form a single straight line inclined towards the cooling pipe outlet for only a small portion of each rotation of the furnace. The cooling pipe 3 then finds itself in a rotational position wherein the material being cooled is fed from one conical pipe portion to the next as though on an inclined shoot. Rotary movement in the direction of arrow 14 means that this position of cooling pipe

3 favorable to the conveyance of the material ceases again after a brief duration. For the material, whose position in the cooling pipe is also continuously changed by the rotary motion, there are now steps rising towards the cooling pipe outlet, these being most marked in the position of cooling pipe 5.

55 In positions with steps rising towards the cooling pipe outlet, i.e. during the major part of each revolution, only a small proportion, or even none, of the material, depending on the amount in the cooling pipe, can be passed from one conical pipe portion into the next. This ensures that the material will 60 stay in the cooling pipes for a long period, and this leads to intensive cooling.

FIG. 3 shows a form of the invention slightly varied from the first embodiment. The cooling pipes 15, 16 and 17 are disposed in this case exactly as in the first embodiment. The difference lies in the construction of the pipes themselves. They consist of conical pipe portions whereof those end faces do not terminate in the outlet housing 13 lie in planes which run obliquely to the longitudinal axis of the corresponding pipe portion. This means that there is an obtuse angle between the main surface and the end face at the points in the individual pipe portions where the major part of the material is held up (i.e. at the points where the step is highest). This simple construction provided by the invention prevents agglomerations of material at positions where this is a special danger.

The cooling pipes 18, 19, 20 and 21 of the rotary tubular furnace 1 shown in FIGS. 4 and 5 differ slightly in shape from those seen in FIGS. 1 and 2, in that the conical pipe portions are axially parallel and offset by approximately the size of the minor diameter of the cone. Since particularly large steps are produced in this way, this embodiment is most generally chosen when the material is required to stay an especially long time in the cooling pipes.

Finally, similar advantages are also provided by the embodiment shown in FIGS. 6 and 7. Here the conical portions 22, 23 and 24 of the cooling pipes are offset by so much (i.e. by about the total of the major and minor cone radii) that transition pieces, preferably conical (e.g. 25 and 26) are provided between the individual pipe portions, and also chutes (e.g. 27 and 28) dropping in the direction of feed. This embodiment also provides a particularly long cooling path in the individual cooling pipes, with effective use of the space available at the periphery of the rotary furnace.

We claim:

1. A rotary tubular furnace with a cooler comprising a number of cooling pipes disposed in satellite manner on the periphery of the tubular furnace, said pipes conically widening in the direction of material flow, and having their inlet connected by a feedpipe to the outlet of the rotary tubular furnace, characterized in that each cooling pipe comprises at least two conical pipe portions disposed in axial sequence and having their axes offset in parallel from each other by at least the difference between the major and minor cone radii.

2. A rotary tubular furnace as in claim 1 wherein the rotary tubular furnace is inclined, characterized in that the conical

inclination of the conical pipe portion is at least twice as great as the inclination of the rotary tubular furnace.

3. A rotary tubular furnace as in claim 1 wherein the rotary tubular furnace is inclined, characterized in that the conical inclination of the conical pipe portion is two to four times as great as the inclination of the rotary tubular furnace.

4. A rotary tubular furnace as in claim 1, characterized in that the axes of the conical pipe portions of all the cooling pipes lie on the surface of an imaginary cylinder concentric with the rotary tubular furnace.

5. A rotary tubular furnace as in claim 1 wherein said cooling pipes have outlets in an annular array around the axis of said furnace and including a common annular outlet housing surrounding the rotary tubular furnace concentric with the outlets of the cooling pipes.

6. A rotary tubular furnace as in claim 1, characterized in that each end face of a conical pipe portion lies in a plane running perpendicularly to the longitudinal axis of the pipe portion.

20 7. A rotary tubular furnace as in claim 1, characterized in that at least some end faces of the conical pipe portions lie in planes which are parallel to each other and inclined to the longitudinal axis of the conical pipe portions.

8. A tubular furnace as in claim 1, characterized in that the 25 conical pipe portions are axially parallel and offset from each other by at least the total of the major and minor cone radii, and in that conical transition pieces are provided at the connection points between the conical pipe portions, together with chutes inclined in the direction of feed of the material.
